ATTORNEY

UNITED STATES PATENT OFFICE.

RALPH H. BINNS, OF NEW YORK, N. Y.

BLOTTER.

Application filed April 30, 1923. Serial No. 635,417.

To all whom it may concern:

Be it known that I, RALPH H. BINNS, a citizen of the United States, residing at New York, in the county of New York and State of New York, have invented certain new and useful Improvements in Blotters, of which the following is a full, clear, and exact description, such as will enable others skilled in the art to which it appertains to make and use the same.

My invention has reference to a blotter, and aims to provide a device of this character which will be particularly useful in connection with a desk set, and which will present an extremely neat appearance in that the blotter may be manufactured of a material of the same type as that of which the desk set is constructed.

It is a further object of the invention to provide a hand blotter capable of being constructed of metal, and which may be shaped to form the blotter parts by means of a die-stamp operation, thus permitting of the manufacture of this article at a nominal figure.

A still further object of the present invention is that of constructing a device of the type aforementioned, with which a blotting material may be readily associated, or from which said material may readily be removed; the construction of this device being such, however, that when the blotting material is disposed in operative relation to the said device, no movement of these parts with respect to one another will occur.

Another object of the invention is that of providing a blotter adapted to be grasped by the hand of the operator, and with which a blotting element will be associated, this element being so disposed on the article that an ample blotting surface will be presented, so that there is no danger of smearing the surface which is being blotted.

Still another object of this invention is that of presenting a device of the character described, which may be more readily manipulated to perform a blotting operation, than blotters as heretofore constructed.

Other objects of the invention will be in part obvious and will in part appear hereinafter.

The invention accordingly comprises an article of manufacture possessing the features, properties, and the relation of elements which will be exemplified in the article hereinafter described and the scope

of the application of which will be indicated in the claims.

For a fuller understanding of the nature and objects of the invention, reference should be had to the following detailed description taken in connection with the accompanying drawings, in which:

Fig. 1 is a bottom plan view of one form of a blotter embodying my improved construction and showing certain parts of the same broken away to disclose the overlying structure;

Fig. 2 is a top plan view of the said blotter, and also showing certain of the parts broken away to disclose the underlying structure;

Fig. 3 is an enlarged transverse sectional view taken on the lines 3—3 and in the direction of the arrows in Figs. 1 and 5;

Fig. 4 is an end view of an element which forms a part of the device aforementioned;

Figs. 5 and 6 are partly sectional, bottom and top plan views respectively of another form of blotter and illustrating certain of the parts as broken away to disclose the construction of other of the parts beyond the same;

Fig. 7 is a bottom plan view of a still further type of blotter embodying the improved construction of the invention;

Fig. 8 is an end elevation thereof;

Fig. 9 is a still further form of the invention; and

Fig. 10 is a transverse sectional view thereof.

It will be seen in all these views that the blotter includes a cover or blotter carrier 10, which has its diametrically opposite edges inturned as at 11, to provide grooves 12, these grooves acting as hereinafter described to retain a blotting member properly associated with said cover.

Attention being invited to Figs. 1 to 6, it will be seen that this retention is accomplished by utilizing a plate 13, which is of a width slightly less than the distance between the base of the opposed grooves 12, so that the plate may readily be brought to a position at which its edges are housed within these grooves, the central portion of the plate aforementioned being thickened in any suitable manner, such as for example by attaching a supplemental plate 14 to one of its faces, the thickness of this latter portion being substantially equal to the thickness of

the blotting member which is utilized. It is here to be noted that those edges of the thickened portion which lie adjacent to the inturned edges of the cover 10, terminate in a plane short of these latter edges, this construction being particularly apparent in Fig. 3. At points beyond the thickened portion of the plate, this member is bent inwardly so that its edges are offset, as has been indicated at 14', to an amount substantially equal to the depth of the thickened portion, so that when the plate is associated with the cover, the body of the former will have its outer face lying in substantially the same plane as the outer faces of the inturned edge portions 11.

In Figs. 1 and 2, the cover has been shown as having its inturned edges extending longitudinally of its body, and accordingly the offset edges of the plate 13 in this instance also extending longitudinally of its body. In the views referred to, it is preferred to recess or notch the ends of the thickened portion as has been indicated at 15, and the plate 13 may have teeth 16 struck up within the spaces thus provided. In assembling the parts the ends of a blotting member 17 are cut to substantially conform to the shape of these recesses or notches, and are brought to extend within the same, the body of the blotting member bearing against the outer face of the plate 13.

In the construction shown in Figs. 5 and 6, which illustrate substantially a reversal of the construction illustrated in Figs. 1 and 2, the inturned edges of the cover are provided at opposite ends of the latter, and the offset edges of the plate are correspondingly formed. Likewise the thickened portion of this plate has its longitudinal edges notched or recessed as at 17, and the blotting member is cut to substantially correspond to these notches, so that the longitudinal edges to this member may extend into these recesses, its body bearing against the outer face of the plate.

In use, referring to the construction embraced in Figs. 1 to 6, it will be understood that a blotting member 18, is provided as aforesaid with its ends corresponding substantially in shape to the recessed portions of the plate with which it is to be associated, and that the body of the former is brought to lie flush against the outer face of the latter, the ends of the blotting member being bent to extend into the recesses or notches aforementioned, at which points they may each be engaged by a tooth 16, providing that the latter is utilized. The plate may now be brought to a position at which its offset edges are housed within the grooves of the cover, and due to the construction adopted, it will be noted first, that the area of the blotting member may be such that it not alone covers the entire outer face of the

plate, but also that it covers the inturned edge portions 11 of the cover. Thus it will be impossible for a surface being blotted to be smeared, due to the fact that none of the parts of the blotter, other than the blotting member, can possibly come in contact with this surface. Due to the offset edges of the carrying plate, the surface of the blotting member is at all times held, so as to prevent any possibility of this member becoming wrinkled. Also, for the reason that a thickened portion is provided, a proper and snug fit will always exist between the cover ends of the blotting member, and all parts of the plate, and consequently none of these parts will become distorted. Upon it being desired to separate the blotting member from the carrying plate, it will be obvious that this may be accomplished with the expenditure of a minimum of time and effort, in that it will only be necessary to slide the plate and cover in opposite directions with respect to each other, thus separating these parts and rendering the blotting member readily accessible for the purposes of removal and renewal. As aforesaid, the construction in Figs. 7 to 10, embraces a cover formed with inturned edge portions to provide grooves adjacent its opposite edges, but it will become apparent upon examination of these views that the same illustrates a more simple embodiment of the invention than that which is embraced in Figs. 1 to 6. By the construction shown in the figures first referred to, the carrying plate may be entirely dispensed with, the attachment between this element and the blotting member being in this instance accomplished by direct engagement of the edges of the blotting member 18 with the grooves 12, provided by the inturned edge portions 11 of the cover plate, it being obvious that these parts are attached to, or detached from one another, by simply sliding the same in opposite directions.

With a view of providing a blotting member which may readily be manipulated to insure a thorough blotting of the surface to which the blotter is applied, it will be noted that the cover may be curved so that this element, as well as the blotting member carried thereby, will have a rocking contact with the surface to be blotted, and this curvature is preferably transverse of the cover, so that an operator by simply pressing his fingers against the upper face of this member, will be capable of rocking the same with a minimum amount of effort, it being obvious that a thorough contact will thus be established between the blotting member and the surface being blotted at all points. Also it will be noted, referring to Figs. 7 to 10, that similarly as in Figs. 1 and 2, and 5 and 6, the inturned edge portions of the same may be formed on either the longitudinal or

end edges of the cover, as is found to be most convenient.

Since certain changes may be made in the above article and different embodiments of the invention could be made without departing from the scope thereof, it is intended that all matter contained in the above description or shown in the accompanying drawing shall be interpreted as illustrative and not in a limiting sense.

Thus, it will be apparent that the objects of this invention are accomplished, and it is to be understood that the following claims are intended to cover all of the generic and specific features of the invention herein described, and all statements of the scope of the invention which, as a matter of language, might be said to fall therebetween.

Having described my invention, what I claim as new and desire to secure by Letters Patent, is:

1. A blotter, including a cover, formed with a pair of grooves, and a blotter carrying plate having two of its edges extending into said grooves, said plate being formed with offset portions adjacent said edges.

2. A blotter, including a cover, having its edges inturned to provide grooves, and a blotter carrying plate formed with offset edge portions adapted to extend into said grooves, the thickness of said offset portions being substantially equal to the thickness of said inturned edge portions.

3. A blotter, including a cover, formed with grooves, a blotter carrying plate formed with offset edge portions extending into said grooves, and a thickened portion forming a part of said plate, the depth of said thickened portion being substantially equal to the thickness of said offset edge portions.

4. A blotter, including a cover formed with grooves, a blotter carrying plate formed with offset edge portions adapted to extend into said grooves, and a supplemental plate attached to said first named plate, and being of a thickness substantially equal to the depth of the offset aforementioned.

5. A blotter, including a cover formed with inturned edges providing grooves, a blotter carrying plate adapted to extend into said grooves, a thickened portion forming a part of said plate, the distance between certain of the edges of said thickened portion being less than the distance between the edges of said inturned portions.

6. A blotter, including a cover, a plate movable with respect to said cover, a thickened portion forming a part of said plate, certain of the edges of said thickened portion being recessed to present surfaces extending substantially parallel to the outer face of said plate, and a sheet of blotting material disposed adjacent the outer plate

face and having certain of its edges extending into said recesses.

7. A blotter, including a cover, a plate carried by said cover, a supplemental plate carried by said first named plate, the ends 70 of said supplemental plate being notched.

8. A blotter, including a cover, a sheet metal plate carried by said cover and movable with respect to the same, and a tooth struck out of said plate and adapted to 75 engage a blotting member carried thereby.

9. A blotter, including a cover, formed with inturned edge portions to provide opposed grooves, a blotter carrying plate formed with offset edge portions extending 80 into said grooves, a thickened portion forming a part of said plate, and being of a width less than the distance between the inturned edge portions, the degree of offset 85 of said plate being substantially equal to the thickness of said inturned edge portions, the height of the thickened portion of said plate being substantially equal to the amount of offset aforementioned.

10. A blotter, including a cover, formed 90 with inturned edge portions to provide opposed grooves, a blotter carrying plate formed with offset edge portions extending into said grooves, a thickened portion forming a part of said plate, and being of a 95 width less than the distance between the inturned edge portions, the degree of offset of said plate being substantially equal to the thickness of said inturned edge portions, the height of the thickened portion of said plate being substantially equal to the amount of offset aforementioned, the end 100 edges of the thickened portion being notched and being adapted to accommodate the ends of a blotting member carried by said plate.

11. A blotter, including a cover, formed 105 with inturned edge portions to provide opposed grooves, a blotter carrying plate formed with offset edge portions extending into said grooves a thickened portion forming a part of said plate, and being of a width less than the distance between the inturned edge portions, the degree of offset 110 of said plate being substantially equal to the thickness of said inturned edge portion, the height of the thickened portion of said plate being substantially equal to the amount of offset aforementioned, the end edges of the thickened portion being notched and being adapted to accommodate the ends 115 of a blotting member carried by said plate, and a tooth forming a part of said plate and positioned within the notched portion thereof.

In testimony whereof I affix my signature, in the presence of two witnesses.

RALPH H. BINNS.
